LETTER STOP

Leroy F. McFarlane, Arlington, Va., and William A. Keyes, Memphis, Tenn., assignors to Pitney-Bowes Postage Meter Co., Stamford, Conn., a corporation of Delaware

Application March 11, 1941, Serial No. 382,686

3 Claims. (Cl. 101—242)

This invention relates to a letter stop which is used to correctly position a letter with relation to a printing die before the start of a printing cycle of operation in a postage printing machine.

The device of this invention is particularly adapted for use on a printing drum of a metered mailing machine of the hand crank operated type. In such a machine the common practice has been to align the leading edge of a letter with a line which is scored on the letter feed plate, but owing to carelessness of operators, the letters are very seldom positioned correctly with relation to the scored line. The result of this carelessness is inaccuracy in printing, with the impression either hitting far back from the edge of the letter or running off the edge of the letter.

To overcome this situation, it is proposed to provide a pendant member on the printing drum in such manner that it will project into the path of a letter when the machine is at rest. When the machine is to be operated, a letter is moved forward on the letter feed plate until the leading edge thereof engages the pendant. Upon rotation of the crank, the printing drum is rotated and the printing die upon engaging the letter, will place the impression in correct relation to the leading edge of the letter.

According to the particular construction of the mounting for the pendant, means is provided whereby the said pendant portion may move inwardly, if, upon reaching the full revolution of movement of the drum, the end of the pendant strikes the end of an unusually long letter which has not entirely passed beneath the drum structure. The pendant is also adapted to be rocked sidewardly when placing a tape attachment upon the machine. For information concerning the type of machine for which the device of this invention is intended, also the tape attachment noted above, attention is called to Patent 1,958,355.

It is the principal object of this invention therefore, to provide a flexible letter stop on the printing drum of a rotary printing machine and include means whereby the stop is maintained in a rigid position when engaged by the leading edge of a letter.

It is another object to provide a flexible letter stop for a printing drum which may move inwardly within the drum.

It is a further object to provide a flexible letter stop on a printing drum which is adapted to be deflected sidewardly.

With the above and other objects in view, which will appear as the description proceeds,

the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is 10 illustrated in the accompanying drawing, wherein:

Fig. 1 is a front view of a printing drum with a letter stop thereon, and includes a letter feed plate with a letter engaging the letter stop;

15 Fig. 2 is a vertical sectional view taken along the line 2—2 of Fig. 1;

Fig. 3 is an enlarged view showing a pendant and support, and further shows the angular motion of the pendant;

20 Fig. 4 is a view similar to Fig. 3, showing the longitudinal movement of the pendant within its support;

Fig. 5 is a further enlarged perspective view of the pendant and support, and

25 Fig. 6 shows a fragmentary portion of a letter with a printed stamp thereon.

Referring to the drawing in detail, the essential parts of a printing machine which have a bearing upon the present invention are shown 30 and include a printing drum 10 having a printing die 11 thereon, a letter feed plate 12 and side guide 13, also an impression roller 14, which cooperates with the printing die in effecting a printing operation.

35 A sleeve 15 has its outer wall threaded as at 16 and is adapted to be screwed within the lower end of the printing drum 10, as indicated in Fig. 2. By means of a set screw 9, the sleeve is fixed in an adjusted position. Said sleeve 15 further 40 includes a bore 17 which terminates a predetermined distance above the bottom of the sleeve to form a seat 18, and a diametrically disposed slot 19 is cut through the lower end of the sleeve 15 to a distance slightly above the seat 18.

45 A pendant, generally indicated at 21, comprises a shank portion 22 having a ball shaped head 23, and is adapted to be inserted in the bore 17 in such manner that the shank portion thereof will project below the slotted end 19.

50 After inserting the pendant in the sleeve, the upper end is peened over, as indicated at 24, to prevent the pendant from sliding through the entrance end after it is once assembled.

By means of the slotted end 19, and the seating of the head 23 within the seat 18, the said

pendant is adapted to have angular movement, as indicated by the positions shown in Fig. 3. Rearward angular movement of the pendant, such as disclosed in full lines Fig. 3, is effected when the tape attachment, disclosed in Patent 1,958,355, is attached to the machine, and forward angular movement, such as disclosed in the swing of the pendant to the right of Fig. 3, is effected when the tape attachment is removed from the machine.

When placing a letter L in a printing position, it is moved rearwardly against the guide walls 13 and forwardly from the left to the right along the feed plate 12, as viewed from Fig. 1, to engage the pendant 21. Upon contact of the edge of the letter with the pendant, the said pendant being in a rigid state owing to the position of the shank portion 22 between the walls of the slot 19, the letter will become fixed with relation to said pendant and will be in the correct position to receive an impression from the printing die 11. When the drum 10 is rotated, the printing die 11 will engage the letter and effect the feed of the letter while printing, the further feed of the letter after printing being provided by means of a knurled flange 25 on the printing drum. A letter printed in accordance with the above named method will have a stamp 26 correctly placed thereon as shown in Fig. 6.

Ordinarily the letter will have been printed and ejected from the machine before the pendant again reaches its home position. Occasionally however, the letter may be of such length that the end thereof will not have passed completely beyond the printing position before the pendant approaches same. When this occurs, the end of the pendant will engage the letter, as indicated in Fig. 4, and the ball portion thereof will be moved upward within the bore 17.

It will be seen therefore, that in addition to acting in the capacity of a letter stop, the pendant 21 is also flexible for movement in both an angular and longitudinal direction.

It will be further seen that the use of such a

device in the manner described, produces an improvement in the correct placing of stamp impressions upon letters, which previously was possible only when operators were very careful to align the letters with a scored line on the letter feed plate.

Having described the invention, what is claimed is:

1. In a device of the character described, the combination with a rotary printing drum and letter feed plate; of a pendant depending downwardly from the drum and capable of rocking and longitudinal movement, and means to block rocking movement of the pendant when a letter is moved into engagement with the pendant during the placing of the letter in a printing position on the letter feed plate.
2. In a device of the character described, the combination with a rotary printing drum; of a pendant, a supporting sleeve mounted within the drum and having the lower end thereof projecting from the lower surface of the drum, said pendant comprising a shank having a ball shaped head supported within said sleeve with the shank end projecting from the lower end thereof, means whereby said projecting shank may move angularly, and means whereby angular motion of the shank is obstructed in one direction.
3. In a device of the character described, the combination with a rotary printing drum; of a pendant, a supporting sleeve mounted within the drum and having the lower end thereof projecting from the lower surface of the drum, said pendant comprising a shank having a ball shaped head supported within said sleeve with the shank end projecting, said sleeve having a diametrically disposed slot in the lower end thereof, whereby said projecting shank may move angularly, and means including one wall of said slot, whereby angular motion of the shank is obstructed in one direction.

LEROY F. McFARLANE.
